CLAIM

The ornamental design for an off-road vehicle as shown and described.

DESCRIPTION

FIG. 1 is a top-front-left side perspective view of an off-road vehicle embodying our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The portions of the off-road vehicle shown in broken lines form no part of the claimed design.
